UNITED STATES PATENT OFFICE.

FRANCES D. SHAW, OF CHICAGO, ILLINOIS, ASSIGNEE TO SHAW KILN COMPANY, OF ATLANTA, GEORGIA, A CORPORATION OF GEORGIA.

CONTINUOUS KILN.

1,194,556.

Specification of Letters Patent. Patented Aug. 15, 1916.

Application filed December 19, 1910. Serial No. 598,053.

To all whom it may concern:

Be it known that I, FRANCES D. SHAW, a citizen of the United States, residing in Chicago, in the county of Cook and State of Illinois, have invented a certain new and useful Improvement in Continuous Kilns, of which the following is a full, clear, concise, and exact description, reference being had to the accompanying drawings, forming a part of this specification.

My invention relates to continuous kilns, and is particularly concerned with kilns which are adapted to burn brick and various forms of pottery, such as is disclosed in my copending application, Serial No. 544,183, filed February 16, 1910. Broadly, kilns of the kind referred to comprise a long tunnel through which cars loaded with the articles to be burned are passed, this tunnel being divided into sections, each definite and peculiar section for the purpose of successively carrying out the various steps of a burning process. Thus, the first section is constructed particularly to drive the water from the molded forms which are to be burned; the second section is constructed to subject the articles to a gradually increasing degree of heat; the third section is constructed to subject the articles to intense heat, while the fourth section is constructed to allow the articles to gradually cool as they pass therethrough and therefrom.

My present invention is particularly useful in connection with the type of kiln above outlined, but it will appear that it may also be just as well employed in connection with other forms of kilns.

The improvement which I now contemplate involves the form of the burning chambers which are associated with that section of the kiln in which the articles under treatment are subjected to the most intense heat, that is, the third section hereinbefore referred to. I propose a special form of chamber whereby the burning gases are directed into the kiln chamber in a particular way so as to secure their even distribution upon the articles which are under treatment. This I secure, as will be hereinafter pointed out, by providing the kiln chamber and the combustion chambers with a long roof, such that the under side thereof will be even, regular and unbroken, so that the gases, in their natural course, will be guided most effectively.

I provide a further improvement in that section of the kiln wherein the articles to be burned are primarily heated. In this section the articles to be burned are gradually heated so that any moisture retained thereby is driven therefrom and so that they are brought into proper condition to enter the burning chamber or burning portion of the kiln, where they are finally subjected to the most intense influence. In this primary heating chamber it is necessary and desirable that the drafts be under absolute control since not only is the moisture disposed of in that way but the primary heating is thereby regulated. The new feature which I have proposed in this connection comprises a plurality of side outlets for the chamber as distinguished from a top outlet, the heated air currents, which would tend to rise, being thus held or "bagged" in an efficient manner. Each of the outlets which are used to complete the draft system is individually regulated and improved means is provided for control in this respect. Furthermore, as a matter of construction, an improved arrangement of stacks for these outlets is provided.

My invention is embodied in the structure illustrated in the accompanying drawings, in which—

Figure 1 is a more or less diagrammatic plan view of the complete kiln of my invention; Fig. 2 is a cross-sectional view taken on the plane of the line 2—2 of Fig. 1; Fig. 3 is a partial elevational view of the burning section of the kiln; Fig. 4 is a cross-sectional view taken on the plane of the line 4—4 of Fig. 3; Fig. 5 is a partial elevational view of the primary heating section of the kiln; and Fig. 6 is a sectional view taken on the plane of the line 6—6 of Fig. 2 and looking in the direction indicated by the arrows.

Like reference characters are applied to the same parts throughout the figures.

Referring first to Fig. 1, the drying section of the kiln is shown at 11, the heating section at 12, the burning section at 13, and the cooling section at 14. It is to be understood that the articles to be burned enter at 105 the drying chamber, and, passing through the tunnel-like structure, leave at the cooling chamber 14. The specific construction of the drying section of the kiln has nothing to do with the present invention and will 110

therefore not be described in detail. Suffice it to say that in my prior application referred to this chamber is described as being provided with a metallic roof upon which the moisture driven from the articles to be burned may condense, suitable means being then provided to carry off the water.

The primary heating chamber 12 is shown in detail in Figs. 2, 5 and 6. It will be seen that practically the entire structure is masonry and, in fact, the parts most closely concerned with the inside of the kiln are refractory brick. The primary foundation is conveniently a concrete structure 15, which, in its various forms, extends practically throughout the entire length of the kiln. This concrete structure has a longitudinal trench 16, in which conveying mechanism (not shown), which is provided for the purpose of carrying cars loaded with the articles to be burned through the kiln, is disposed. It will be seen that the primary heating chamber has side walls 17, 17, which are of masonry suitably reinforced by longitudinal beams 18, 18. An arch roof 19 connects these side walls and completes the longitudinal tunnel through which the cars, abutting end to end, may pass. These cars run upon rails 20, 20, suitably mounted upon cross bars 21, 21 set in masonry in a finished manner. The side walls 17 are each provided with a shelf 22, upon which an inverted V rail 23 is disposed, a sand seal 24 being disposed in the resulting trough for a purpose hereinafter pointed out. At the beginning of the heating chamber 12 and near the end thereof there is provided a supplementary structure 25 of masonry, which comprises, first, the auxiliary wall 26, which, together with the main wall 17, forms the flue 27, these walls being extended a considerable distance above the roof 19. The two extensions thus provided are connected by beams 28 and tie rods 29 for strengthening purposes, and are further connected by a cross flue structure 30, the cross flue 31 itself connecting with the vertical flues 27, 27, as best shown in Fig. 2.

Each of the flues 27 connects with the kiln chamber proper by means of the passageways 32, 32. At the center of the cross flue structure 30 an outlet 33 is provided and this outlet is supplemented by a suitable stack 34, the entire arrangement being braced by vertical tie rods 35, 35. Each of the flues 27 is provided with a damper 36, which passes through a slot and rides in grooves in the wall 26 and is adapted to enter an lining pocket 37 in the wall 17. This damper is shown in Figs. 2 and 6 and may be set entirely to close the flue. As is apparent from Fig. 5, this damper is accessible from the outside and may be set in any desired position while the kiln is in operation. The air which passes from the

kiln chamber through the passageways 32 and upwardly through the flues 27 and the stack 34 is always more or less laden with moisture and as it cools this moisture is condensed on the sides of the stack. The water thus formed may run down through the stack and the cross flues and may become deposited in the bottom of the flues 27, 27, from which it may be withdrawn in any suitable manner. Since these drafts are drawn from the sides of the kiln chamber, the tendency for that chamber to retain the heat induced from the burning section is greatly enhanced.

Referring to Figs. 3 and 4, it will be seen that the primary supporting structure of concrete is changed in form to accommodate the enlarged refractory walls 38, 38, which have the externally exposed pockets 39, 39, in which the oil burners 40, 40 are disposed. Each of these oil burners is in the form of a reticulated tube 41, which extends downwardly into a pan 42. Fuel is fed to this burner by means of a short pipe 43, which terminates in a funnel 44 to which short pipes 45 and 46 lead from the main pipes 47 and 48, respectively. Valves 49, 49 are provided for obvious purposes. In the operation of this oil burner the arrangement is first heated to a considerable extent so that the fuel upon reaching it will become volatilized and the combustible mixture will pass upwardly through the passageway 50 into the burning chamber 51. As shown in Fig. 4, such a burning chamber is provided on each side of the main kiln chamber, and the arched roof 52, somewhat analogous to the arched roof 19 hereinbefore described, is so constructed and mounted that it forms a common closing means for the main kiln chamber and the burning chambers 51, 51. Suitable bracing means for the entire structure is provided in the way of vertical beams 53, 53 and tie rods 54. As in the other section of the kiln which has been described, rails 20, 20 are provided upon suitable cross bars 21, 21, set in the masonry and the shoulder 22 on each of the side walls is continued for continuation of the sand seal 24. As has been hereinbefore stated, the cars are placed upon the rails and are arranged to abut each other end to end so that a moving floor is in effect secured. One of the cars is shown at 55 in Fig. 4. Upon each side of the car is provided with a downwardly extending flange 56, which extends into the sand seal 24, so that the heat is confined to the chamber above the car. The primary floor of the car is adapted to ride under a shoulder 57 extending inwardly into the kiln chamber from each of the side walls, this shoulder extending throughout the length of the primary heating section and the burning section of the kiln and throughout the entire length, if desired. Below

this shoulder the car is provided with a sand seal 58 and this seal acts to assist the other sand seal in confining the heat to the chamber as we described. The hole 59, 59 may 5 be provided for purposes of observation during the operation of the kiln.

The cars 55 carry the articles *a*, *a* which are to be treated, and it is clear that burning takes place between the roof 52 and the 10 floor of the car 55. Since the roof 52 is continuous over the burning chambers 51, 51 and the main kiln chamber, the gases which burn therein will be gradually directed over toward the main kiln chamber because of 15 the arch-like form of the roof. Since the under side of the roof is an even continuous surface the gases will follow this surface, and where, in the center, they meet, coming from opposite sides, they will be 20 brought downwardly. This will tend to coax the gases down upon the articles to be burned evenly throughout the aggregate area thereof. Because of the form of the roof and its 25 relation to the main chamber and the burning chambers, the gases will sweep naturally over toward the center and there will be little tendency for eddy currents and more action at one place than at another. The 30 result is that all the brick or other articles are evenly burned. The improved control of the primary heating chamber which has been described is effective in preventing the water from dropping upon the articles to be burned and is also generally effective in 35 securing a better brick.

I claim as new and desire to secure by Letters Patent:—

1. In a kiln, the combination of a burning section, a pre-heating section, said burning section comprising a kiln chamber, a combustion chamber at each side of said kiln chamber, a common roof for said chambers, 40

and a car adapted to be carried through said pre-heating section and kiln chamber in immediate proximity to said roof. 45

2. In a kiln, the combination of a burning section, a pre-heating section, said burning section comprising a kiln chamber, a combustion chamber at each side of said kiln chamber, a common roof for said chambers, 50 and a moving floor disposed within said pre-heating section and kiln chamber in immediate proximity to said roof.

3. In a kiln, the combination of a burning section, a pre-heating section, said burning section comprising a kiln chamber, a combustion chamber at each side of said kiln chamber, an arched roof covering said sections, and a car adapted to be carried through said pre-heating section and kiln chamber in immediate proximity to said roof. 55

4. In a kiln, the combination of a burning section, a pre-heating section, said burning section comprising a kiln chamber and a combustion chamber on the side of said kiln chamber, an arched roof covering said chambers, and a car adapted to be carried through said pre-heating section and kiln chamber in immediate proximity to said roof. 60 65

5. In a kiln, in combination, a primary heating chamber, a vertical flue on each side of said chamber, a side outlet connecting said chamber with said flue, and a well communicating with each of said flues and disposed below said outlet. 70 75

In witness whereof, I hereunto subscribe my name this 12th day of December, 1910.
